UNITED STATES PATENT OFFICE.

RUDOLF WOLF, OF MAGDEBURG-BUCKAU, GERMANY.

SHAFT-GOVERNOR FOR ENGINES.

1,038,055.

Specification of Letters Patent. Patented Sept. 10, 1912.

Application filed May 16, 1912. Serial No. 697,656.

To all whom it may concern:

Be it known that I, RUDOLF WOLF, manufacturer, a citizen of the German Empire, residing at Magdeburg-Buckau, Germany, 5 have invented certain new and useful Improvements in Shaft-Governors for Engines, of which the following is a specification.

My invention relates to improvements in 10 shaft governors for engines, and more particularly to shaft governors which are mounted on one of the crank arms of the crank shaft, and the object of the improvements is to provide a governor of this class 15 which has a large regulating power, and which is compact in construction, it being possible to limit its dimensions so that it shall be not much larger in diameter than the double of the outer radius of the crank 20 arm.

With this and other objects in view my invention consists in arranging the fly balls or bodies and their coöperating springs at opposite sides of the crank arm and with 25 their axes parallel thereto, and in such a way that the fly balls or bodies move under the influence of centrifugal force in a direction parallel to the crank arm.

For the purpose of explaining the invention 30 an example embodying the same has been shown in the accompanying drawing, in which the same letters of reference have been used in all the views to indicate corresponding parts.

35 In said drawing Figure 1 is a cross-section of the governor taken on line I—I in Fig. 2, and Fig. 2 is a side view thereof seen in direction of the arrow II partly in section.

40 Referring to the example illustrated in the drawing, the operative parts of the governor are mounted within a frame or casing H in the form of a drum which is secured to one of the crank arms B of the crank 45 shaft D. Within the drum or casing H is a pair of spring-members, one consisting of coil springs F₁, f₁ and the other of coil springs F₂, f₂ each member having one of its ends connected to the casing, and its opposite end to fly balls or bodies G₁, G₂. As 50 shown each of the spring members consists of two sections, viz. an outer section F₁ (and F₂) and an inner section f₁ (and f₂),

the inner section being mounted on and secured to a collar f₅ (and f₆) slideable on a 55 stem f₃ (and f₄), and the outer section being connected at one end to the said collar and at the opposite end to the coöperating fly body G₁ (or G₂). The inner ends of the inner springs f₁, f₂ abut against fixed col- 60 lars on the inner ends of the respective rods f₃ and f₄ and, their rods are affixed to the casing. By thus disposing the spring sec- 65 tions one within the other a compact construction is obtained because the strength- 70 ening of the one spring is compensated for by shortening of the other spring. The springs F₁, f₁ and F₂, f₂ are disposed on opposite sides of the crank arm and parallel thereto. The centrifugal forces exerted 75 on the fly bodies G₁ and G₂ act in radial directions, as has been indicated by the letter C, and this force acts by two components C₁ and C₂, the component C₁ being in the direction of the springs F₁, f₁ and F₂, f₂, 80 and the component C₂ being perpendicular thereto. To take up the component C₂ the fly bodies G₁ and G₂ are guided on guide ways I₁ and I₂ respectively, and in order to reduce the friction to a minimum anti-fric- 85 tion rollers or ball bearings K₁ and K₂ are interposed between the fly bodies and their guide ways.

The fly bodies are provided with pivot 90 bolts Z₁, Z₂ by means of which they are connected to bell crank levers W₁, W₂ which are pivotally mounted on the casing H at L₁ and L₂ respectively. The said bell crank levers are connected with the eccentric E by levers A₁, A₂ which are jointed to the 95 bell crank levers at P₁ and P₂. The circular paths of the pivots P₁ and P₂ are congruent with the curve described by the eccentric when being set. The rod E₁ of the eccentric 100 E acts upon the inlet valve of the engine in a manner not shown in the drawings as these parts of the engine can be made in any known way.

In the preferred form of the governor the fly bodies G₁ and G₂ are so mounted rela- 105 tively to the springs F₁, f₁ and F₂, f₂, that their centers of gravitation are at a slight distance away from the axes of the springs, which distance has been indicated in the drawing by the letter a. Thereby the fly bodies exert a pressure on the arms W₁ and

- W₂ of the bell crank levers, which pressure is in the direction of the said arms and causes friction in the fulcrums of the bell crank levers sufficient to dampen the reacting forces.
- 5 In governors as now constructed the eccentric-rod and the valve stem operating the valve must ordinarily be connected by means of a rocker or the like. In my improved construction such members for transmitting the movements of the eccentric laterally are entirely dispensed with, because the slide or other valve (not shown) may be located within the central plane of the eccentric.
- 10 Having now particularly described and ascertained the nature of my said invention and in what manner the same is to be performed, I declare that what I claim is:—
- 15 1. In a governor for steam engines, the combination with a shaft having a crank arm, of a casing mounted on said crank arm, a pair of coil spring members each attached at one end to a relatively fixed part of the casing and disposed upon opposite sides of and parallel with the crank arm, a fly body coöperating with each of said spring members, means adapted to guide said fly body in a direction substantially parallel to the crank arm, and means adapted to operatively connect said fly body with the mechanism for controlling the engine.
- 20 2. In a governor for steam engines, the combination with a shaft having a crank arm, of a casing mounted on said crank arm, a pair of coil spring members each attached at one end to a relatively fixed part of the casing and disposed upon opposite sides of and parallel with the crank arm, a fly body coöperating with each of said spring members, means adapted to guide said fly body in a direction substantially parallel to the crank arm, and means adapted to operatively connect said fly body with the mechanism for controlling the engine.
- 25 3. In a governor for steam engines, the combination with a shaft having a crank arm, of a casing mounted on said crank arm, a pair of coil spring members each attached at one end to a relatively fixed part of the casing and disposed upon opposite sides of and parallel with the crank arm, a fly body coöperating with each of said spring members, means adapted to guide said fly body in a direction substantially parallel to the crank arm, and means adapted to operatively connect said fly body with the mechanism for controlling the engine, said guiding means embodying an anti-friction bearing.
- 30 4. In a speed governor, the combination with a casing and a fly body, of a coiled spring member coöperating with said fly body and constructed in two sections disposed one within the other and connected at one of their ends with each other and with the opposite ends respectively to the fly body and to a relatively fixed part of said casing.
- 35 5. In a speed governor, the combination with a casing and a fly body, of a coiled spring member coöperating with said fly body and constructed in two sections disposed one within the other, a stem passing through said spring sections and secured to a relatively fixed part of said casing, and a sleeve slidably mounted on said stem, said spring sections having one of their ends connected to said sleeve and their opposite ends respectively to said stem and to the fly body.
- 40 6. In a speed governor for engines and other purposes, the combination with a frame or casing adapted to be mounted on a crank arm, of two spring members secured at one of their ends to relatively fixed parts and respectively disposed when the governor is mounted on the crank arm at the opposite sides of and parallel to the crank arm, fly bodies coöperating with said spring members, means to guide said fly bodies in a direction parallel to the crank arms, and means adapted to operatively connect said fly bodies with the mechanism for controlling the engine.
- 45 7. In a speed governor for engines and other purposes, the combination with a frame or casing adapted to be mounted on a crank arm, of two spring members secured at one of their ends to relatively fixed parts of the casing and respectively disposed when the governor is mounted on the crank arm at the opposite sides of and parallel to the crank arm, fly bodies coöperating with said springs, means including antifriction bearings to guide said fly bodies in a direction parallel to the crank arms, and means adapted to operatively connect said fly bodies with the mechanism for controlling the engine.
- 50 8. In a speed governor for engines and other purposes, the combination with a frame or casing adapted to be mounted on a crank arm, of two spring members secured at one of their ends to relatively fixed parts of the casing and respectively disposed when the governor is mounted on the crank arm at the opposite sides of and parallel to the crank arm, fly bodies coöperating with said springs and located with their centers of gravitation respectively at a distance away from the axis of said spring members, means to guide said fly bodies in a direction parallel to the crank arms, and means adapted to

operatively connect said fly bodies with the mechanism for controlling the engine, said means comprising levers respectively jointed to said fly bodies and disposed substantially in the direction of the forces caused by the location of the fly bodies away from the axes of the springs.

In testimony whereof I hereunto affix my signature in presence of two witnesses.

RUDOLF WOLF.
